UNITED STATES PATENT OFFICE.

JOHN W. SMITH AND JAMES M. COUGHLIN, OF LIBERTY, INDIANA, ASSIGNORS
OF ONE-THIRD TO NOAH L. HECKMAN, OF LIBERTY, INDIANA.

DISK GRAIN-DRILL.

SPECIFICATION forming part of Letters Patent No. 716,774, dated December 23, 1902.

Application filed July 5, 1902. Serial No. 114,505. (No model.)

To all whom it may concern:

Be it known that we, JOHN W. SMITH and JAMES M. COUGHLIN, of Liberty, in the county of Union and State of Indiana, have invented 5 a new and useful Improvement in Disk Grain-Drills, of which the following is a specification.

Our invention relates to improvements in disk grain-drills, and has for its object to provide a grain-drill which shall be simple, compact, and efficient. Heretofore in devices of this character the seed-conduit has been usually located on the convex side of a concavo-convex disk and made in one piece. In our 15 device the seed-conduit is made in two sections, the upper one being located on the concave side of the disk and the lower section on the convex side thereof, the two sections communicating through a hollow hub carrying 20 the disk.

Our invention further consists in certain novel constructions and combinations of parts, as will be hereinafter fully described, and pointed out in the claims.

25 Figure 1 is a vertical section through the disk and seed-conduits. Fig. 2 is an elevation of the inside of the disk and attached drag. Fig. 3 is a similar view of the outside of the disk, showing lower seed-conduit and drag-bar. Fig. 4 is a view of the inside face of the lower seed-conduit.

In carrying out our invention we use, preferably, a concavo-convex disk A, having a central circular opening into which is bolted 35 an annular flanged ring a, forming a boxing. Said boxing fits on the hub B, which is provided with a downwardly-extending lug b, provided with a curved groove b'. The upper side of the hub is also provided with a 40 curved groove, with the same radius as the groove in the lug b. Within the groove the inner edge of the ring a fits and is adapted to revolve. Extending upwardly from the hub and preferably integral therewith is the 45 curved upper seed-conduit C, which extends upwardly at least to the periphery of the disk A and preferably beyond it. The seed-conduit C extends into or preferably through the hub in a curved line and has its discharge 50 end at the convex side of the disk.

Secured on the convex side of the disk A is the lower seed-conduit D, which is provided on its inner face with the inwardly-extending flange d, which is arc-shaped and adapted to fit over and bear upon the periphery of the 55 annular flange of the ring boxing a. Said lower seed-conduit is secured adjustably to the hub B by means of a screw-bolt d', passing through a curved horizontal slot d² therein and screwing into the hub. The lower 60 seed-conduit D is provided with a forwardly-extending lug or arm D', provided with a curved diagonal slot D², by means of which and a bolt d³ it is secured to drag-bar E. Projecting from the inner face of the lower 65 seed-conduit D are the lugs D³ D⁴, between which is journaled an antifriction-roller D⁴, adapted to bear against the edge of the boxing a of the disk A.

The hub B on the concave side of the disk 70 is provided with the horizontal extension B', which projects to the front and rear of its center, said extension being channeled to receive the drag-bar E', which is secured in the channel by bolts e.

The lower seed-conduit is also provided on its inner face with the curved ribs or flanges D⁵, which extend from about the center of the upper circular portion to the lower end of the 75 said conduit, the edges of said flanges 80 forming in curvature to the convex face of the disk A. The inner upper edges of the conduit D are curved inwardly and also fit the convex face of the disk A. The outer face of the conduit D has secured to it near its 85 upper portion the drag-bar E by the bolts before mentioned. The lower seed-conduit D has a rearward inclination, and its lower end is never to extend beyond the periphery of the disk.

90 By adjustably connecting the lower seed-conduit with the hub and drag-bar by the curved slots the said conduit may be moved in the arc of a circle, thereby permitting the seed to be placed in the ground at a greater 95 or less depth with the same amount of pressure and also permits the placing of the seed in a wide or narrow seed-bed, as desired, without moving or changing the position of the upper seed-conduit. By making the seed- 100

conduits in two sections, as shown, we are able to place the upper seed-conduit on the concave side of the disk, and thus prevent dirt and trash accumulating between the upper seed-conduit and the concave side of the disk.

By placing the upper seed-conduit on the concave side of the disk and by curving the lower end of said conduit, as shown, the seed in rolling over the curve in the lower end of the upper seed-conduit will be more evenly distributed than would be the case if the upper seed-conduit were in a perpendicular position.

15 While this device is shown applied to a concavo-convex disk, it will also work efficiently on a flat disk, and as it consists of few parts it is manifest that it can be manufactured very cheaply.

20 Having thus described our invention, what we claim as new, and desire to secure by Letters Patent, is—

1. In a seeding device, a disk a hub secured thereto having a passage therethrough, 25 upper and lower conduits communicating with said passage whereby seed may be conveyed from the upper seed-conduit to the lower seed-conduit.

2. In a seeding device a disk, a hub secured thereto and provided with a passage therethrough, an upper seed-conduit located on one side of the disk and communicating at the lower end thereof with the passage through the hub, the upper end of said conduit extending to or above the periphery of said disk.

3. In a seeding device a concavo-convex disk, a hub secured thereto and provided with a passage therethrough, a seed-conduit on the convex side of said disk, the upper end of the said conduit communicating with the passage through said hub and the lower end of the said conduit extending to or adjacent to the periphery of the disk.

4. In a seeding device, a disk, a hub secured thereto and provided with a passage therethrough, a seed-conduit the upper end of which communicates with the passage through said hub, and means for adjustably securing said conduit to the hub, whereby the conduit may be moved in an arc and held, to deposit seed in the soil at a greater or less depth.

5. In a seeding device, a disk, a hub secured thereto and having a passage therein, 55 an upper seed-conduit located at one side of said disk the lower end of said upper conduit communicating with the passage in the hub, and a lower seed-conduit located at the opposite side of the disk, the upper end of the lower seed-conduit communicating with the passage in the hub.

6. In a seeding device, a disk, a hub provided with a passage therethrough and secured to the disk, an upper seed-conduit located at one side of said disk and communicating at its lower end with the passage through the hub, a lower seed-conduit located

at the opposite side of the disk said lower conduit communicating with the passage through the hub and provided with a forwardly-extending lug or arm at its upper end and having a diagonally-disposed curved slot therein and a bolt passing through said slot whereby the said lower conduit may be adjusted in an are to deposit seed at a greater or less depth. 75

7. In a seeding device, a hollow hub, a disk revolvably secured thereto, a seed-conduit secured to the hub at one side of the disk, and antifriction-roller secured to the inner face of the seed-conduit and adapted to bear against the adjacent face of the disk.

8. In a seeding device, a hub having a passage therethrough, a disk revolvably secured thereto, an upper seed-conduit located at one side of the disk and communicating at its lower end with the passage through the hub, a lower seed-conduit located on the opposite side of the disk and communicating at its upper end with the passage through the hub and provided with a horizontally-disposed curved slot in its upper portion, and a bolt passing through said slot and adjustably securing the said lower seed-conduit to the hub whereby the said conduit may be adjusted to place the seed in varying width of seed-bed. 95

9. In a seeding device, a hub having a passage therethrough, a disk revolvably mounted thereon, an upper seed-conduit located at one side of the disk and having a curved lower end, said curved end communicating with the passage through the hub, and a lower seed-conduit located on the opposite side of the disk, and communicating at its upper end with the passage through the hub. 100

10. In a seeding device, a hub provided with a curved passage therethrough, a disk revolvably mounted on said hub, an upper seed-conduit located at one side of the disk and communicating at its lower end with the curved passage through the hub, and a lower seed-conduit located at the opposite side of the disk, and communicating at its upper end with the said curved passage through the hub. 105

11. In a seeding device, a hub having a passage therethrough, and provided with curved bearing-grooves, a disk provided with an annular flanged ring boxing, adapted to bear in the curved bearing-grooves, and revolvably mounted on said hub, an upper seed-conduit located at one side of the disk and communicating at its lower end with the passage through the hub, a lower seed-conduit located on the opposite side of the disk, and communicating at its upper end with the passage through the hub, said lower conduit provided 115 at its upper end with a curved flange adapted to surround the annular flanged ring boxing and curved flanges extending from its inner face and adapted to bear against the adjacent face of the disk, and means for adjustably securing the lower seed-conduit to the hub. 120

12. In a seeding device, a hub provided with a curved passage therethrough, a channel in one end of the hub, a disk revolvably mounted

- on said hub, an upper seed-conduit located at one side of the disk and communicating at its lower end with the passage through said hub, a lower seed-conduit located at the opposite side of the disk and communicating at its upper end with the passage through the hub, and drag-bars secured respectively in the channel in the hub and against the outer face of the lower seed-conduit.
13. In a seeding device, a revoluble disk suitably supported, and provided with a conducting-passage extending through its center from the inside to the outside thereof, whereby seed may be conducted from the inner side

of the disk through the center thereof and deposited at the outer side of the disk.

14. In a seeding device a revoluble disk provided with a conducting-passage extending through its center from the inside to the outside thereof and a seed-conduit located at the outer side of said disk, the upper end of said conduit communicating with the passage through the center of the disk.
